Chas. Lynn Russell
his ATTORNEY

UNITED STATES PATENT OFFICE

CARL F. SCHULZ, OF BROOKLYN, NEW YORK

INVISIBLE SUSPENDER ATTACHMENT

Application filed April 2, 1932. Serial No. 602,650.

This invention relates to devices for permitting a person to wear the suspenders for supporting his trousers under his dress shirt, one of the objects of the invention being to provide a device of this character which is simple, comfortable, efficient and practical which, while in position on the body, is easily attached to and detached from the waist band of the trousers and which can readily be used in conjunction with the suspender buttons ordinarily found upon trousers.

Another object of the invention is to provide a device of this character which not only affords a practical connection between an invisible suspender and the waist band of the trouser, but also serves to clamp and securely hold in position the lower portion of the dress shirt upon which the suspenders are worn.

Another object of the invention is to provide a simple and efficient button engaging member for a device of this character.

Another object of the invention is to provide, in a device of this character, a button engaging device which is capable of accommodating buttons set at various distances apart.

Another object of the invention is to provide a device of this character having means for engaging the buttons at the waist band of the trouser and passing downwardly and then upwardly in the nature of a loop for receiving the adjacent portion of the wearer's shirt and in association therewith elastic means for engaging the shirt at this region and holding it in position.

A still further object of the invention is to provide, in a device of this character, means located well up toward the waist band of the trouser for engaging the wearer's undergarments.

In the drawing accompanying this application there is illustrated one practicable embodiment of the invention, in which drawing:

Figure 1 is a perspective view of a form of one of my attachments shown disconnected from the garments and from the suspenders, and two hinged members swung somewhat apart to give a better view of their construction.

Fig. 2 is a side elevation, certain parts hav-

ing been removed to show the construction and location of other parts, and

Fig. 3 is a front elevation of the portions of the device which normally occupy a position between the body of the wearer and his outer shirt.

The main body of the device is preferably formed of some non-corrosive or rust resisting wire bent into proper form. The preferred embodiment of the invention comprises two portions hinged together, one part being intended for connection to a suspender end and the other for application to the waist band of the trousers.

The suspender engaging member, or more properly the portion of the device which directly depends from the suspender end, is illustrated in the form of a rectangular wire frame 5, to the upper end of which is secured, in some suitable manner, a flexible loop 6 intended for attachment to the end of the suspender. To the lower end of this member 5 is secured another rectangular frame 7 which is normally upstanding and designed for being secured to the waist band of the trousers. The lower end of the member 5 has an outwardly projecting bracket portion 8 for the purpose of causing the lower end of the trouser engaging portion to stand away from the lower end of the suspender engaging portion.

In the preferred form of the device this outwardly projecting bracket portion 8 is formed from the free ends of the wire 5, it having an upper run 9 at its upper portion around which the base member 10 which carries the loop 6 passes. At the lower ends of the wires forming the rectangle 5 each wire is given a bend as at 11 around a lower or cross wire 12, the ends 13 of which are hooked around over the eye members 11 for preventing the spreading apart of the ends 8. These ends of these members 8 are bent back into the form of eyes 14 which pass around the inwardly turned lower ends 15 of the wire forming the member 7. These ends 15 are really the free ends of the wire which are enclosed by a tube 16 which serves the function not only of holding these ends in proper

55

100

relative positions, but also holds the eyes 14 apart.

It will thus be seen that the cross member 12 with its hooks 13 prevent the lower portion of both members from spreading, and that the tube 16 prevents the lower ends of both members from approaching one another. The ends 15 are further held together by means of a cross-brace 17 which has its 10 ends formed as eyes 18 bracing the lower portion of the wires forming the frame 7. To keep the cross-brace 17 in its proper position the wires 7 are shown inwardly bent as at 19 where they are embraced by the eyes 18.

15 The upper portion of the oblong frame or trouser supporting member carries the trouser or button engaging portions of the device which, in the present instance, is bent from the central portion of the wire. Each 20 of the wires forming the sides of the oblong 7 is bent at substantially right angles, laterally as at 20. It is then bent up in the form of a loop 21, the end of which is bent sharply as at 22. The wire then proceeds in a 25 straight line 23 extending from loop to loop and paralleling and preferably closely engaging the wires 20—20. These loops 21 on their inner sides are given a pronounced inner bend 24, the purpose of which is to receive an endless band 25 preferably formed of flexible substantially inelastic braided material such as is used for shoe laces.

30 The portion of the device just described is intended for engaging the ordinary suspender buttons which are placed on the inside of the waist band of the trousers. The wire, sufficiently rigid to perform its desired functions, is nevertheless sufficiently elastic and the band 25 is sufficiently flexible to permit the buttons to pass through the spaces 35 between the endless band 25 and the wires 23 and 20. The necks of the buttons rest on the wire 23 and under severe load press it somewhat forward so that the necks then rest 40 upon both wires 23 and 20.

In use a number of these devices, preferably one at each side and one at the back, have their loops 6 engaged with some connecting device on the pair of suspenders.

45 The suspenders are preferably worn under the outer shirt of the wearer. It permits the lower end of the shirt to occupy the space between the members 5 and 7 and places the waist band of his trousers outside of the member 7 and the button engaging portion, which for convenience may be regarded as represented by the endless band 25.

50 When applied as above indicated the suspenders will be concealed from view and the entire device herein illustrated will also be concealed from view.

55 In many instances it is found desirable to employ some device for positively, and preferably elastically, engaging the shirt where 60 it is folded between the members 5 and 7 to

prevent it becoming displaced. In the present illustration there is shown a strip of elastic 27 secured to the center portion of the wire 23 and passing down and around the wire 12 and extending upwardly and between the side wires of the member 5 and there furnished with a clip or clamping device 28 which may be similar to the devices used in hose supporters. The upper or outer end of the elastic band is preferably held in position by means of a piece of fabric or leather 29 which is preferably sewn to the elastic webbing 27 and loops around the center portion of the run of wire 20, and loops as at 30 over the front run of the endless band 25, a row of stitching 31 preferably separating the portion 30 from the portion which embraces the wire 23.

65 This organization supports the various parts and prevents the buttons from coming loose. It may also be found desirable to employ a clip or fastening member 32 for engaging the underwear of the user of the device, in which case such a clip is carried by the extended end 33 of the elastic band or 70 webbing 27.

75 It is to be noted that when the parts 5 and 7 are in substantially the position shown in Fig. 2 the upward pull on the loop 6 and the downward pressure on the frame will be communicated to it from the buttons through the wires 20—20 and 23. The tendency of the 80 two members is to approach one another, this being effected by the offset connection afforded by the outwardly extending wires or 85 arms 8. This closing together movement of these members is augmented by the pull exerted on the parts by the webbing 27 and clip member 28 when this is tightly applied to the shirt of the user.

90 As can be readily understood by the inspection of the drawing, together with the description which has preceded, downward pressure exerted by the underwear clamped in the clip 32 also tends to hold the parts in 95 their proper positions, or at any rate, this downward pressure, when the parts are in their normal position, does not tend to separate the two members of the device.

98 It will be apparent that changes may be made within the scope of the claims without departing from the spirit of the invention.

Having thus described my invention, what I claim and desire to secure by Letters Patent is:

1. In a device of the character specified comprising a wire frame of rectangular formation having at its upper portion laterally extending arms bent into upstanding loops, the opposed sides of the loops having inward bends, an endless band passing through such loops and adapted for secure attachment to the waist band of a pair of trousers, the frame being adapted to extend below the point of attachment, and a member 100

extending from the lower end of such frame to a point above the points of waist band attachment and there provided with means for the engagement of a suspender.

5 2. The combination with a frame member having at its upper portion means for the engagement of a suspender, the other or lower end of the device having short, outwardly directed arms, a member adapted to be secured

10 to the waist band of a pair of trousers and upstanding from the outer ends of such arms, and having at its upper portion laterally directed arms furnished with trouser engaging portions.

15 3. The combination with a frame member having at its upper portion means for the engagement of a suspender, the other or lower end of the device having short, outwardly directed arms, a member adapted to be secured

20 to the waist band of a pair of trousers hinged-ly carried by the outer ends of such arms and having at its upper portion laterally directed arms furnished with trouser engaging portions.

25 4. In a device of the character specified, the combination with a frame having laterally extended arms provided at the ends with upstanding loops, the opposed sides of the loops having inward curves, of an endless band of flexible material passing through such loops, there being a button receiving space between the endless band and each of the laterally extending arms.

30 5. A device of the character specified comprising a dependent suspender engaging portion, a waist band engaging portion secured to and upstanding from the lower end of said dependent portion and having lateral extensions formed with upstanding loops, a band of flexible material extending from loop to loop, a strip of elastic material secured to the upper end of the waist band engaging portion and constructed and adapted to extend below and around such lower end, and a garment clasp carried by such strip of elastic material.

35 6. A device of the character specified comprising a dependent suspender engaging portion, a waist band engaging portion secured

40 to and upstanding from the lower end of said dependent portion and having lateral extensions formed with upstanding loops, a band of flexible material extending from loop to loop, a strip of elastic material secured to the upper end of one of the members and con-

45 structed and adapted to extend below and around such lower end, a garment clasp secured to such strip of elastic material, a second strip of elastic material secured to the

50 upper end of such waist band engaging portion and dependent therefrom, and a garment clasp secured to such dependent elastic strip.

55 7. A device of the character specified comprising a wire frame of a rectangular forma-

60 tion having in its upper portion laterally

extending arms bent into upstanding loops, an endless band passing through such loops, a member comprising a wire frame of rectangular formation hingedly connected to the lower end of the first named frame, the upper end of this frame having means for engaging a suspender, a band passing over a portion of the laterally extending arms and the endless band and adapted to pass below and around the hinged connection between the frames, and a garment clasp carried by such band.

65 8. A device of the character specified comprising a wire frame of a rectangular forma- 60 tion having in its upper portion laterally extending arms bent into upstanding loops, and endless band passing through such loops, a member comprising a wire frame of rectangular formation connected to the lower end of the first named frame, the upper end of this frame having means for engaging a suspender, there being a cross bar at the lower end of one of these frames, an elastic band secured to the upper portion of one of the frames and extending below and around the cross bar, and a garment clasp carried by such elastic band.

70 9. A device of the character specified comprising a dependent suspender engaging portion, a waist band engaging portion up- 65 standing therefrom, elastic means extending upwardly from the lower end of the device, and clamping means carried thereby.

75 10. A device of the character specified, comprising a dependent suspender engaging portion, a portion secured to and upstanding from the lower end of said dependent portion and having lateral extensions formed with waist band engaging terminals, and a band of flexible material extending from terminal to terminal.

80 11. A device of the character specified comprising a dependent suspender engaging portion, a spreading waist band engaging portion secured to and upstanding from the lower end of said dependent portion, the terminals of said waist band engaging portion being connected, a band of yieldable material extending from terminal to terminal of said waist band engaging portion, a strip of elastic material secured to the upper end of one of the members, and constructed and adapted to extend below and around such lower end, a garment clasp secured to such strip of elastic material.

85 12. A device of the character specified comprising a dependent suspender engaging portion, a waist band engaging portion up- 110 standing therefrom, elastic means secured to the upper end of one of the members, and constructed and adapted to extend below and around such lower end, a garment clasp secured to such strip of elastic means.

90 13. A device of the character specified comprising a suspender engaging portion, a 115

waist band engaging portion upstanding therefrom, elastic clamping means carried by one of the members.

14. In a device of the character specified, 5 the combination with a frame having laterally extended arms provided at the ends with upstanding loops, of an endless band of flexible material passing through such loops, there being a button receiving space between 10 the endless band and each of the laterally extending arms.

15. A device of the character specified, comprising a dependent suspender engaging portion, a portion secured to and upstanding 15 from the lower end of said dependent portion and having laterally extended arms provided at their ends with means adapted for the connection of a flexible band, and a band of flexible material connected thereto, 20 the arms and the band forming an elongated button receiving orifice.

16. A trouser engaging device comprising

a framework formed at its upper portion with a laterally elongated enclosed button receiving slot, the frame also being formed with a downwardly extending portion, an elastic band secured at one end to the upper 70 portion of the frame extending downwardly and around the lower portion of the frame, and a self-contained garment clasp carried by the free end of such elastic band.

17. A trouser engaging device comprising 75 a framework formed at its upper portion with two laterally elongated enclosed button receiving slots, the frame also being formed with a downwardly extending portion, an elastic band secured at one end to the upper portion of the frame extending downwardly and around the lower portion of the frame, and a self-contained garment 80 clasp carried by the free end of such elastic band.
